ABSTRACT

The reel comprises first and second expandible shell portions and expanding and clamping means which are operable to expand said shell portions and to clamp a strip end portion. The expanding and clamping means comprise a radially movable clamping bar, which is coupled to said second shell portion and adapted to cooperate with said first shell portion to clamp a strip end portion. The second shell portion is pivotally movable and forms a transition member adapted to guide a strip portion adjacent to said clamped strip end portion. Each of said shell portions extends peripherally from a free end disposed adjacent to the other shell portion to a pivoted end. The clamping bar engages said free end of said first shell portion and is adapted to clamp said strip end portion against said free end of said first shell portion and is radially outwardly movable to expand said shell portions. A bearing is provided, in which said pivoted end of said second shell portion is mounted and which permits said second shell portion to perform a pivotal movement and a movement substantially in the direction in which said bar is radially movable. Said bar is coupled to said free end of said second shell portion so that said second shell portion is moved substantially in the same direction as said bar during a radially outward movement of said bar.

REEL FOR COILING STRIP

This invention relates to an improved reel for coiling strip, particularly metal strip, in plants for manufacturing and/or processing strip.

Known reels for coiling strip, particularly metal strip, comprise a shell which includes two hinged expandable shell portions, which are adjustable by means of a radially displaceable expanding bar, which engages the shell portions adjacent to their free ends. In these known drums, one of the expandable shell portions defines a gap, in which an end of the strip can be clamped.

The prior U.S. Pat. application Ser. No. 251,177 now U.S. Pat. No. 3,774,862, filed May 8, 1972, discloses a reel for coiling strip, particularly metal strip in plants for manufacturing and processing strip, which consists of preferably pivoted expandable shell portions, which are adjustable by expanding bars, and a pivotally movable transition member.

It is an object of the invention to improve the reel disclosed in said prior application so that both a reliable damping of the strip and a satisfactory transition of the strip from its clamped portion to the coil are ensured.

In a reel for coiling strip, particularly metal strip, in plants for manufacturing and/or processing strip, which comprises preferably pivoted, expandable shell portions, which are adjustable by means of expanding bars, and a pivotally movable transition member, this object is accomplished in that the transition member is coupled to a radially movable clamping bar by interengaging therewith, one expandable shell portion and the displaceable clamping bar are adapted to clamp the strip whereas the other expandable shell portion, which is coupled to the clamping bar, serves as a transition member.

A reel for coiling strip, particularly metal strip in plants for manufacturing and/or processing strip, which comprises two pivoted expandable shell portions, which are adjustable by means of a radially movable expanding bar, which engages the shell portions adjacent to their free ends, one of said expandable shell portions defining a gap in which a strip end position can be clamped, is improved in accordance with the invention in that the gap is defined between the free end of said one expandable shell portion and the associated engaging surface of the expanding bar, and that the second expandable shell portion is coupled to the expanding bar and is held in a bearing so as to be pivotally movable and displaceable substantially in the same direction as the expanding bar. In such an arrangement, the second expandable shell portion, which is mounted to be pivotally movable and displaceable, is held against the engaging surface of the expanding bar by a spring which acts in the direction of the pivotal movement, and is held in coupling engagement with a step of the expanding bar by a returning spring acting in the direction in which the shell portion is displaceable.

The bearing for the second expandable shell portion permits of a pivotal movement and a displacement thereof and preferably comprises a member which has the form of a segment of a cylinder and which is rotatable in a recess defined by a part-cylindrical surface and has a flat side face with which the second expandable shell portion is in sliding contact. In such an arrangement, the pivotally movable and displaceable, ex-

pansible shell portion extends around about 90° of the periphery of the reel.

An embodiment of the reel according to the invention is shown by way of example on the drawing and will be described hereinafter.

FIGS. 1 and 2 are, respectively, a transverse sectional view and a longitudinal sectional view showing a reel according to the invention.

FIGS. 3 and 4 are enlarged sectional views showing the clamped and transitional portions of strip of different gages.

As is apparent from FIG. 1, the reel comprises at the portion in which the leading end of the strip is to be clamped an expandable shell portion 7a, which is pivotally movable in an outward direction from the remaining part of periphery of the reel. The expandable shell portion 7a serves also as a transition member and is coupled to a radially displaceably mounted expanding bar 8 by interengaging therewith at a step 9. A clamped leading end of strips 10 and 11 of different gages is shown in FIGS. 3 and 4, respectively. The expanding bar cooperates with a projection 12 of another expandable shell portion 7b, which serves as a clamping member for clamping the leading end of the strip. The expanding bar 8 is seated in a longitudinal groove 13 and together with the projection 12 defines a narrow gap 14.

It is also apparent from FIG. 2 that the reel is mounted only at one end at 15. The expanding bar 8 is provided with guide pins 8a, which engage a centrally disposed wedge bar 16, which is axially displaceable in both directions C, e.g., by pneumatic or hydraulic means.

The expandable shell portion 7b which serves as a clamping member is hinged at 17 and terminates in the projection 12 having a flat surface, which defines the gap 14 with the expanding bar 8. A spring 18 urges the expandable shell portion 7b against the expanding bar 8, which in turn holds the expandable shell portion 7b in engagement with a stop 19 formed in a reel body 6.

The expandable shell portion 7a which serves as a transition member is mounted in a bearing 20 so as to be pivotally movable and displaceable and by a spring 21 is held in interengagement with the expanding bar 8 at a step 9 so that the shell portion 7a is coupled to the bar 8. The bearing 20 for the expandable shell portion 7a serving as a transition member comprises a member in the shape of a segment of cylinder. Said member is rotatable in a part-cylindrical, concave recess 22 and has a flat surface 23 with which the expandable shell portion is in sliding contact. A return spring 24 acts on the angled stop portion 25 and serves to return the expandable shell portion 7a and to hold it in coupling engagement. As is particularly apparent from FIGS. 3 and 4, the expandable shell portion 7a serving as a transition member extends around 90° of the periphery of the reel so that the bearing 20 and the return spring 24 cooperate to ensure a displacement of the shell portion 7a at its end coupled to the expanding bar 8. As is apparent from FIGS. 3 and 4, the coupling arrangement and the flat transition prevent a formation of kinks in the transitional portions of the strip between the clamped and coiled portions thereof.

What is claimed is:

1. A reel for coiling strip, which comprises first and second expandable shell portions each having a free end and each of said shell portions extending peripherally

from said free end disposed adjacent to the other shell portion to a pivoted end,

an expanding and clamping bar, which engages said free end of said first shell portion and clamps a strip end portion against said free end portion of said first shell portion and which is radially outwardly movable to expand said shell portions, and a bearing, in which said pivoted end of said second shell portion is mounted and which limits said second shell portion to perform a pivotal movement and a movement substantially in the direction in which said bar is radially movable, said bar being engaged with said free end of said second shell portion so that said second shell portion is moved substantially in the same direction as said bar during a radially outward movement of said bar.

2. A reel as set forth in claim 1, in which said bar is wedge-shaped at the surfaces engaging said free end portions of said shell portions, a first spring is provided which tends to move said second shell portion in the direction in which it is pivotally movable toward said first shell portion and to hold said free end portion of said second shell portion against one of said wedge-shaped surfaces, and

a second spring is provided, which tends to move said second shell portion opposite to the direction in which said bar is radially outwardly movable and to hold said second shell portion in coupling engagement with said bar.

3. A reel as set forth in claim 1, in which said bearing comprises means defining a part-cylindrical recess and a member having the shape of a segment of a cylinder having on one side a peripheral surface in sliding

contact with the surface of said recess so that said member is rotatable in said recess, said member having on the opposite side a flat surface extending substantially in the direction in which said bar is radially movable and in sliding contact with said second shell portion.

4. A reel as set forth in claim 1, in which said second shell portion forms the periphery of said reel in an arc of about 90°.

5. A reel as set forth in claim 1, in which said second shell portion is a transition member adjacent to said clamped strip end portion.

6. A reel as set forth in claim 1, in which said bar is formed with a step, which is in coupling engagement with said second shell portion.

7. A reel for coiling strip, which comprises a reel body formed with a stop, said reel having attached thereto first and second expansible shell portions and expanding and clamping means which expand said shell portions and to clamp a strip end portion, said expanding and clamping means comprising a radially movable clamping bar, which is in engagement with said second shell portion and cooperates with said first shell portion to clamp a strip end portion, said second shell portion being pivotally movable and forming a transition member to guide a strip portion adjacent to said strip end portion with said stop on said reel body being engageable with said first shell portion to limit the expansion thereof in response to radially outward movement of said clamping bar.

8. A reel as set forth in claim 7, in which a means is provided for urging set first shell portion against said clamping bar.
